J. W. GILLIAM:
GAGE ADJUSTING TOOL.
APPLICATION FILED JUNE 26, 1920.

1,387,383.

Patented Aug. 9, 1921.

INVENTOR

JAMES W. GILLIAM,
by James L. Hopkins, ATTORNEY.

UNITED STATES PATENT OFFICE.

JAMES W. GILLIAM, OF PEVELY, MISSOURI.

GAGE-ADJUSTING TOOL.

1,387,383.

Specification of Letters Patent.

Patented Aug. 9, 1921.

Application filed June 26, 1920. Serial No. 392,126.

To all whom it may concern:

Be it known that I, JAMES W. GILLIAM, a citizen of the United States, residing at Pevely, in the county of Jefferson and State 5 of Missouri, have invented certain new and useful Improvements in Gage-Adjusting Tools, of which the following is a specification, reference being had therein to the accompanying drawing.

10 My invention relates to a gage adjusting tool, and its object is to provide a tool for use in railway track laying, to aid in rapid adjustment of a rail to the required gage.

In the drawings—

15 Figure 1 is a side elevation of a tool embodying my invention.

Fig. 2 is a plan view of said tool.

Fig. 3 is a perspective view showing the tool in place upon a railway track and illustrating its use in connection with the crowbar with which, or some equivalent lever, 20 the tool is intended for use.

In the drawings the bar 4 is of wood or like non-conducting material (to prevent 25 short-circuiting between electrified rails) and carries the plate 5, secured by bolts 6, and having downwardly projecting teeth 7—7. The teeth 7—7 are so spaced as to engage the ball of the rail 8. At its opposite extremity

the bar 4 (the length of which bar 4 is determined by the gage of the track) carries the slotted plate 9, secured to it by bolts 10. The plate 9 has a longitudinal slot 11, the length of which is such that when in use the slot will be evenly balanced over the ball 35 of the rail 14, having a space at each side of said rail-ball through which the lever 15 may be inserted, the ends of the slot 11 being the fulcruming edges 12 and 13. By the lever 15 the rail 14 is adjusted inwardly 40 or outwardly with relation to the rail 8, and when in proper gage is spiked or otherwise secured in position.

Having described my invention what I claim is—

A gage adjusting tool comprising a bar; a plate secured to one end of said bar and having downwardly projecting teeth so spaced as to engage the ball of a rail; and another plate fixed to the other end of said 50 bar and having a longitudinal slot of such length as to be evenly balanced over the ball of the other rail and having a space at each side of said rail-ball, substantially as described.

In testimony whereof I hereunto affix my signature.

JAMES W. GILLIAM.
